FOCUS DETERMINING DEVICE FOR
PHOTOGRAPHIC ENLARGERS

William D. Thompson, San Diego, Calif.

Application October 24, 1946, Serial No. 705,442

3 Claims. (Cl. 88—24)

1

This invention relates to a focus determining device for photographic enlargers, and has for its principal object the provision of a small, compact, easily used instrument by means of which it may be ascertained when a photographic enlarger is in perfect focus with the enlarging screen.

The invention is more particularly designed for use on the enlarging apparatus illustrated and described in applicant's co-pending application, Serial No. 705,441, now abandoned. It is, however, not limited to this particular use but will be found valuable with any conventional enlarging apparatus.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a vertical section through the projection head of a conventional photographic enlarging projector, illustrating the invention in place therein;

Fig. 2 is a side view of the improved focus determining device;

Fig. 3 is a front view thereof;

Fig. 4 is a horizontal section, looking upwardly on the line 4—4, Fig. 2;

Fig. 5 is a detail view of a removable door, the removal of which allows the improved focus determining device to be inserted in the enlarger; and

Fig. 6 is a face view of a focusing target which may be used with the improved enlarger.

The improved focus determining device is to be used with any enlarger having a light source, a film holder, and a projecting lens system and is designed to be placed between the light source and the film holder.

In Fig. 1 the typical parts of a conventional enlarging apparatus are illustrated and designated by numeral as follows: condenser lens barrel 10; lens head chamber 11; objective lens collar 12; objective lens barrel 13; objective lenses 14; and condensing lenses 15. The apparatus illustrated is provided with a film holder 16 of any desired type in which the film to be enlarged is indicated at 17.

In the enlarging device illustrated, the cham-

2

ber 11 is provided with a doorway in its side normally closed by a removable door 18, shown in detail in Fig. 5. The door is normally held in place by means of snap springs 19 and can be removed simply by pulling with sufficient force to release the springs 19 from the doorway. When in use the improved focus determining attachment replaces the door 18.

In use, the enlarger is brought to an approximate focus by means of the eye of the operator. The door 18 is then removed and the focusing device is placed in the door opening to determine the final focus.

The focus determining device carries a door plate 20 of a size and shape to occupy the position of the door 18 so as to seal the chamber 11. The door plate 20 is provided with snap springs 21 which engage the edges of the door opening to hold the plate 20 in place thereon.

20 A hollow housing 22 projects inwardly from the door plate to provide a guide for a lens barrel 23. The lens barrel is slidably mounted in a guide partition 24 in the housing 22 and is threaded through the door plate 20 so as to project outwardly therefrom. An annular locking nut 25 is threaded on the barrel 23 to lock it in any desired position in the door plate 20.

The lens barrel 23 is provided with objective lenses 26 adjacent its inner extremity and carries 30 an eye piece 27 threaded into its outer extremity. The eye piece carries a magnifying lens 28 which cooperates with the lenses 26 to project a magnified image into the eye of the operator. The image is received from a 90° reflecting device, which may be a mirror or a prism. 35 As illustrated, an inclined mirror 29 is used, preferably silvered on its front face.

The mirror 29 is supported at an angle of 45° from the vertical by means of two bracket arms 30 extending from the end of the housing 22. 40 The bracket arms 30 support the mirror 29 at the optical axis of the objective and condensing lenses 14 and 15, and at a position above the film 17, that is, between the film and the light source of the enlarger.

45 If the enlarging objective lenses 14 are out of focus with the enlarging screen, the mirror 29 will reflect two images into the eye of the user. If these lenses are in perfect focus with the screen, only a single image will be reflected. 50 One of these images consists of a picture of the film itself, for since the back of the film is brilliantly illuminated, a perfect image thereof will be reflected and projected in magnified form to the operator's eye. The other image is due to

the fact that the objective lenses 14 will act in the nature of camera lenses and throw an image of the illuminated picture, which is being projected upon the enlarging easel, back upon the film 17, which acts as a translucent projection screen.

In other words, if a screen were positioned at the place of the film and an illuminated picture were placed upon the enlarging easel, a reduced image of this picture would be thrown upon the screen. The same thing occurs upon the film when the film 17 occupies the position of the screen. The picture in the latter case consists of the illuminated image projected by the enlarger. This projected image will only coincide with the original picture on the film 17 when the objective lenses 14 are in perfect focus. This can be easily determined by the operator, since the lenses 26 and 28 greatly magnify the double image on the film.

The door plate 20 and the snap springs 21 are simply illustrative of one method of detachably inserting the focusing device in the light cone of an enlarging device. Other means could be employed for detachably inserting the device, depending, of course, upon the particular structure of the enlarging device in question. The principal feature of the invention resides in providing means for projecting an image of the film to one side of the optical axis of the enlarging device so that a comparison may be made between the actual emulsion picture and the returned projected picture thereof.

While the improved focus determining device has been illustrated and described as removable, it could be built in permanently, if desired. Tests made with a $\frac{1}{2}''$ x $\frac{1}{2}''$ mirror and a foot-candle meter show but a slight deviation of the indicating needle and no difference is discernible with the eye in the light striking the easel when the focusing device is removed and replaced. However, since the device is no longer needed after the focus is set, it can be removed, if desired.

For thin negatives, or negatives without contrasty detail, focusing is facilitated by means of a focusing target 31 (see Fig. 6), which may be placed on the enlarging board or easel. The clear areas of the film negative then act as a "ground glass" upon which the image of the target is focused by means of this improved focusing device. The target should be relatively large, say $8''$ x $10''$.

The threads on the lens barrel 23 are for the purpose of focusing the magnifying lens system on the negative with the eyes of the individual user to obtain the most perfect focus possible. After being focused and set by means of the nut 25 it will remain fixed as long as the same person uses the device. This particular focusing has nothing to do with the focusing of the enlarger. It is only for obtaining the best results with each user.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A focus determining device for photographic enlargers comprising: condensing lenses; objective lenses, all of said lenses being positioned in axial alignment so that said condensing lenses will refract a conical beam of light through said

objective lenses; a photographic film having a developed image interposed in said beam of light between said condensing and said objective lenses with its front surface facing said objective lenses so that an illuminated picture of said image will be projected upon an enlarging easel; a reflecting device positioned in said beam of light between said condensing lenses and said film and having its reflecting surface directed toward said film at an angle as to reflect light from the rear surface of said film outwardly at a substantially 90° axis from the optical axis of said lenses; and means for viewing the rear surface of said film as reflected from said reflecting surface.

2. A focus determining device for photographic enlargers comprising: condensing lenses; objective lenses, all of said lenses being positioned in axial alignment so that said condensing lenses will refract a conical beam of light through said objective lenses; a photographic film having a developed image interposed in said beam of light between said condensing and said objective lenses with its front surface facing said objective lenses so that an illuminated picture of said image will be projected upon an enlarging easel; a mirror positioned in said cone of light between said condensing lenses and said film, said mirror being substantially smaller than the light beam so as to intercept only a relatively small fraction of the light and having its reflecting surface directed toward said film at an angle being to reflect an image of a portion of the rear side of said film outwardly from said optical axis; and magnifying lenses positioned to receive the light reflected from said mirror for viewing said rear side of said film.

3. The combination in a photographic enlarger of a lens chamber; condensing lenses positioned at one extremity of said barrel; objective lenses positioned at the other extremity of said chamber in axial alignment with said condensing lenses; a film holder positioned in said chamber between said condensing and objective lenses; a photographic film in said holder; a lens barrel extending radially into said chamber through the wall thereof between said condensing lenses and said holder; viewing lenses in said lens barrel; a mirror; and bracket means supporting said mirror substantially at the intersection of the optical axis of said condensing and objective lenses, said mirror being positioned at an angle of 45° to both said axes and facing said holder so as to reflect light from said film through said viewing lenses.
